U.S. Cl. D34—5

FIG. 1

FIG. 1 is a front elevational view of a swing seat or similar article embodying my new design;

FIG. 2 is a cross-sectional view taken on line 2—2 of FIG. 1;

FIG. 3 is a cross-sectional view taken on line 3—3 of FIG. 2;

FIG. 4 is a cross-sectional view taken on line 4—4 of FIG. 2.

The broken line portion seen in FIG. 1 indicates indeterminate length, and the rope is shown partly in FIG. 3 for convenience of illustration.

I claim:

The ornamental design for a swing seat or similar article, substantially as shown and described.
